GAME SELECTOR WHEEL

Perry J. Grant, Pacific Palisades, Calif., assignor to
The Toy Development Center, Inc., a corporation of California

Filed Feb. 6, 1967, Ser. No. 5,702

Term of patent 14 years

(Cl. D34—5)

FIG. 1

The broken line portion in FIG. 1 is an illustrative example as to indicia on the wheel.

I claim:

The ornamental design for a game selector wheel, substantially as shown and described.
